(57) CLAIM

The ornamental design for a pressed coin pendant, substantially as shown and described.

DESCRIPTION

FIG. 1 is a perspective view of a first embodiment of the pressed coin pendant showing my new design;

FIG. 2 is a front view of the pressed coin pendant of FIG. 1.

FIG. 3 is a back view of the pressed coin pendant of FIG. 1.

FIG. 4 is a side view of the pressed coin pendant of FIG. 1.

FIG. 5 is an opposite side view of the pressed coin pendant of FIG. 1.

FIG. 6 is a top view of the pressed coin pendant of FIG. 1.

FIG. 7 is a bottom view of the pressed coin pendant of FIG. 1.

FIG. 8 is a perspective view of a second embodiment of the pressed coin pendant showing my new design;

FIG. 9 is a front view of the pressed coin pendant of FIG. 8.

FIG. 10 is a back view of the pressed coin pendant of FIG. 8.

FIG. 11 is a side view of the pressed coin pendant of FIG. 8.

FIG. 12 is an opposite side view of the pressed coin pendant of FIG. 8.

FIG. 13 is a top view of the pressed coin pendant of FIG. 8; and,

FIG. 14 is a bottom view of the pressed coin pendant of FIG. 8.

The broken lines shown in the drawings represent portions of the pressed coin pendant and form no part of the claimed design.
